UNITED STATES PATENT OFFICE.

AUGUST C. SEEGER, OF EAST ST. LOUIS, ILLINOIS.

FIRE-EXTINGUISHER.

1,147,557.

Specification of Letters Patent. Patented July 20, 1915.

Application filed May 20, 1914. Serial No. 339,792.

To all whom it may concern:

Be it known that I, AUGUST C. SEEGER, a citizen of the United States, residing at East St. Louis, in the county of St. Clair and State of Illinois, have invented new and useful Improvements in Fire-Extinguishers, of which the following is a specification.

This invention is an improved automatic chemical sprinkler and fire alarm for extinguishing fires in buildings and at the same time sounding an alarm, the object of the invention being to provide an improved apparatus of this class which is cheap and simple, is automatic in operation, which requires little or no attention and which is efficient and thoroughly practical in use.

The invention consists in the construction, combination and arrangement of devices hereinafter described and claimed.

20 In the accompanying drawings: Figure 1 is a vertical sectional view of an automatic sprinkler and fire alarm constructed in accordance with my invention, showing the acid bottle and holder in normal position in full lines and in overturned, operating position in dotted lines. Fig. 2 is a detail sectional view on the plane indicated by the line *a—a* of Fig. 1.

Referring to the form of my invention shown in the drawing a suitable tank 1 is provided which in practice contains the usual soda solution. This tank has a cap 2 at its upper end. A delivery pipe 3 leads from the bottom of the tank to a sprinkler 4. Any suitable number of sprinklers may be employed at different points and connected to the said pipe and each sprinkler includes a fusible releasing element 5. A screen 6 is provided in the bottom of the tank 40 and at the intake of the pipe 3. An electric enunciator 7 or other translating device is in circuit with a battery 8 and one of the conductors 9 is normally broken by a movable contact device 10 which is connected by 45 a suitable cord or wire 11 to the releasing element of the sprinkler head. When the said releasing element is fused or otherwise released it relaxes tension on the cord 11 and thereupon the circuit is closed at 10 and 50 the alarm sounded.

A pair of spaced bracket arms 12 are arranged in the tank and connected to the wall thereof and provided at their inner ends with bearings 13 which are engaged by the trunnions 14 of a bottle holder 15. This 55 bottle holder is here shown as cylindrical in form each provided with an opening 16 in the bottom and as having spaced holder arms 17 at its upper end which are inturned toward one another. The trunnions 14 or 60 pivots of the bottle holder are to one side of the center of the bottle holder and on the opposite side of the bottle holder, near its upper end is a weight 18 which when the bottle holder is released by the means and 65 hereinafter stated will cause the bottle holder to be overturned and reversely arranged so that its upper end will be lowermost.

A bottle or other container 19 for acid is 70 arranged in the holder 15 and floats therein on the soda solution in the tank and holder and the mouth 20 of the acid bottle or container is closed by a fixed stopper 21 which is held by an arm 22. A sufficient quantity 75 of the solution is maintained in the tank to keep the acid bottle raised so that its mouth is engaged and closed by the stopper 21 and this stopper also serves to hold the bottle holder in upright position and against the 80 counter-balancing tendency of the weight 18. When the sprinkler head is opened by the fusing of the alarm 5 or otherwise flow of the solution causes its level to be lowered in the tank 1 and hence the acid bottle 19 85 becomes lowered and its mouth disengaged from the stopper 21, whereupon the weight 18 overturns the holder 15 and the acid bottle and causes the contents of the acid bottle to be discharged into the solution in 90 the tank thereby generating gas and discharging the same and the liquid from the sprinkler head and on the fire.

Having thus described my invention I claim:—

95 In apparatus of the class described, a tank having normally closed discharge means, a pivotally mounted holder in the tank, an acid container arranged to float in the holder and having a discharge opening at its upper 100

2
end, a stopper against which the discharge opening is held by the buoyancy of the acid container and means to cause the holder and acid container to be overturned when the acid container is lowered by initial discharge of some of the contents of the tank.

In testimony whereof I affix my signature in presence of two witnesses.

AUGUST C. SEEGER.
